UNITED STATES PATENT OFFICE.

NOBLE TEAS, OF NEWARK, NEW JERSEY, ASSIGNOR TO MARIA J. FRANKS
AND MARY H. TEAS.

HARNESS-SADDLE.

SPECIFICATION forming part of Letters Patent No. 537,247, dated April 9, 1895.

Application filed October 29, 1894. Serial No. 527,167. (No model.)

To all whom it may concern:

Be it known that I, NOBLE TEAS, a citizen of the United States, residing at Newark, in the county of Essex and State of New Jersey, have invented certain new and useful Improvements in Harness Saddle-Trees; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to prevent the saddle, when in use, from being drawn forward upon the horse's back and galling the withers of the animal, and to secure other advantages hereinafter referred to.

20 The invention consists in the improved saddle tree, and in the combination and arrangements of the parts thereof, and connected therewith, as herein set forth and finally pointed out in the claims.

25 Referring to the accompanying drawings, in which similar letters of reference indicate corresponding parts in each of the figures where they occur, Figure 1 represents a plan view of one half of a saddle tree which embodies my invention. Fig. 2 is a plan view 30 of the saddle tree with the wings thereof removed, and Fig. 3 is a plan of one of said wings, the latter being adjustable when upon the tree, as hereinafter stated. Fig. 4 is a 35 plan view showing a modified form of the said saddle tree; and Fig. 5 is a plan view of the saddle showing the leather work attached to the tree.

40 In the present state of the art, metal saddle trees, as a rule, are constructed with the wings or sides at right angles, with a line drawn through the center of the saddle, and when the saddle is on the horse, the front part thereof is apt to come in contact with and gall or chaff the withers of the animal. 45 Efforts have been made, from time to time, to remedy this difficulty, and in some cases to this end, the leather at the front of the saddle has been cut out or recessed so as to throw

the metal saddle tree well back of the leather work, or what is the same, to throw the leather work forward of the saddle tree. It is found, however, that this does not remove the difficulty, because the girth or body band of the saddle, when tightened around the horse's 55 body, tends to work forward and to draw the saddle tree with it on to the withers, with the result above named. Again: it has been sought to remove the difficulty by a stuffing beneath the saddle tree so as to raise the latter 60 above the withers. Another and more frequent remedy for the evil, is to place a thick felt pad under the saddle. This, however, looks bad, and on rainy days, gets soaked with water. All these devices are more or 65 less objectionable, and to avoid their use, I construct the saddle tree with the wings or sides thereof at a greater or less angle than a right angle from a line drawn through the center of the tree. The said wings or sides 70 also project considerably forward of the center of the tree. The said wings or sides may be separate from the center of the tree and capable of adjustment upon the latter at a greater or less angle with the said center 75 line; or they may be made integral with or rigidly connected to said tree.

In the examples shown in the drawings, the wings are at an acute angle from a line drawn through the center of the tree, as will be seen 80 by reference thereto.

In said drawings, A, designates the center of the tree, and B, the wings.

In Fig. 1 the wing B, is secured to the center by means of the terret and a nut on the inner 85 end thereof, the shank of the terret passing through an aperture, a, in the loose wing and through a slot, b, in the center. By means of this construction, I am enabled to increase or decrease the angle of the wing as well as to 90 throw the latter more or less forward of the center, as circumstances or conditions may require, as will be readily understood. The effect of thus making the wings at an acute angle with the line through the center of the 95 saddle, is to throw the saddle back when the girth is strapped tightly around the body of the animal, and prevent it from riding or be-

ing drawn up upon the withers, as will be understood, and by means of the adjustability of the wings, they can be made to conform more perfectly to existing conditions, that is, to animals of different sizes and shapes.

In Figs. 4 and 5, the wings are integral with the center of the saddle, or rigidly secured thereto and intended to be all that is required to meet normal conditions.

10 It will be seen that in all these examples, the check hook will be thrown well back from the withers.

It is intended that the sides of the tree, (in Figs. 1 and 2), upon which the wings B, are adjusted, shall be depressed so that the said wings shall fill said depressions and be flush with the sides of the rigid part of the tree, so that the leather work will cover and fit smoothly thereon, as will be understood. An 15 other advantage in this construction is that the adjustable sides or wings may be made of different widths, and used interchangeably upon the same center, thereby making saddles of several different sizes without changing 20 the size of the center, and also increasing or decreasing the distance between the front end of the tree and the front edges of the wings, as will be evident. That is to say, the wider 25 the wings are made, the farther they may be 30 adjusted forward of the center of the saddle

tree, and hence the latter will be farther removed from the withers of the animal.

Having thus described the invention, what I claim as new, and wish to secure by Letters Patent of the United States, is—

1. A saddle tree, the central portion of which is adapted to receive a saddle, and the sides are each provided with a longitudinal slot, a wing for each side provided with a perforation registering with the slot, a terret, the shank of which passes through the perforation and the slot for adjustably securing the wings to the sides, substantially as set forth. 35

2. A saddle tree, the central portion of which is adapted to receive a saddle, and the sides are each depressed and provided with a longitudinal slot, and a wing for each side provided with a perforation, the top of the wing being flush with the sides of the tree, and a terret, the shank of which projects 40 through the perforation and the slot for holding the parts together, substantially as set forth. 45

In testimony that I claim the foregoing I have hereunto set my hand this 22d day of November, 1894. 55

NOBLE TEAS.
